DESIGN FOR A BOTTLE OPENER OR SIMILAR ARTICLE

Reyburn M. Smith, Evansville, Ind.

Application October 30, 1944, Serial No. 116,044

Term of patent 14 years

(Cl. D44—29)

To all whom it may concern:

Be it known that I, Reyburn M. Smith, a citizen of the United States, residing at Evansville, in the county of Vanderburgh and State of Indiana, have invented a new, original, and ornamental Design for a Bottle Opener or Similar Article, of which the following is a specification, reference being had to the accompanying drawing, forming part thereof.

I claim:

The ornamental design for a bottle opener or similar article, as shown.

REYBURN M. SMITH.
